B. F. KLOHS.

KEYHOLE GUARD FOR MULTIPLE KEY LOCKS.
APPLICATION FILED MAY 1, 1914.

1,118,427.

Patented Nov. 24, 1914.

UNITED STATES PATENT OFFICE.

BARTHOLOMEW F. KLOHS, OF CANTON, OHIO, ASSIGNOR TO THE DIEBOLD SAFE AND LOCK COMPANY, OF CANTON, OHIO, A CORPORATION OF OHIO.

KEYHOLE-GUARD FOR MULTIPLE-KEY LOCKS.

1,118,427.

Specification of Letters Patent.

Patented Nov. 24, 1914.

Application filed May 1, 1914. Serial No. 835,698.

To all whom it may concern:

Be it known that I, BARTHOLOMEW F. KLOHS, a citizen of the United States, residing at Canton, in the county of Stark 5 and State of Ohio, have invented certain new and useful Improvements in Keyhole-Guards for Multiple-Key Locks, of which the following is a specification.

The present invention has to do with that 10 class of locks more especially employed upon safety deposit boxes, in which at least two keys must be employed to open the lock, one key to be retained by the banker or custodian of the safety deposit box, the other 15 key to be retained and used by the depositor. The object and reason for this is that before the safety deposit box or other receptacle can be opened the depositor must be identified as the proper owner of the key carried, 20 before he is permitted to use the key to open the box. In use and for the purpose of proper protection to the depositor it is best that it requires the presence of both the depositor and the banker or custodian to properly 25 manipulate the lock.

The object of the present invention is to provide such means that two keys must be employed and in such a manner that the depositor cannot open the lock nor can the 30 custodian open the box with the key carried by either, without the use of both keys. These advantages and objects, together with other advantages and objects readily apparent to those skilled in the art I attain by the 35 construction illustrated in the accompanying drawing, although my invention may be embodied in a variety of other mechanical forms, the construction illustrated being chosen by way of example.

40 In the accompanying drawing Figure 1 is a partial view showing a portion of a safety deposit box and a portion of the door showing the door locked and the key hole guards in proper position and the seal hasp 45 properly connected. Fig. 2 is a detached view of the seal hasp showing the same closed but not sealed. Fig. 3 is a similar view showing the seal hasp open. Fig. 4 is a front view showing the key hole guards 50 placed in position, both of the guards being shown in their relative positions when inserted, but one of the guards yet to be moved in the position to connect the hasp seal. Fig. 5 is a detached view of the depositor's key 55 hole guards. Fig. 6 is a detached view of

the banker's or custodian's key hole guard. Fig. 7 is a detached view of the depositor's key. Fig. 8 is a detached view of the banker's or custodian's key. Fig. 9 is a view showing transverse sections of the spindles, 60 the position of the tumbler to be actuated by the key, also showing the lock bolt in extended position. Fig. 10 is a view showing the tumbler moved into position by the banker's key. Fig. 11 is a front face view 65 of the spindles showing the position of the door. Fig. 12 is a section taken on line 12-12, Fig. 11.

Similar numerals of reference indicate corresponding parts in all the figures of the 70 drawing.

In the accompanying drawing, 1 represents the lock casing proper, which is attached to the door 2 in the usual manner, to which casing are attached the spindles 3 and 4, said spindles being provided with the key ways 5 and 6, and for the purpose of holding the spindles, the usual sleeves 7 and 8 are provided, which sleeves are connected to the lock casing or in a plate in the usual 80 manner. The specific manner of connecting the spindles 3 and 4 does not have to do with the present invention, except that such parts must necessarily be present. The spindle 3 is the one designed to be actuated by the 85 key carried by or in possession of the banker or custodian, and the spindle 4 is the one designed to be actuated by the key carried by the depositor. Within the lock casing is located at least one tumbler 9, which must be 90 actuated by the key carried by the banker or custodian and cannot be actuated by the key carried by the custodian, nor can the key carried by the custodian be inserted in the key way of the spindle 4, so as to actuate 95 the ordinary tumblers, until after the tumbler 9 has been actuated by the key carried by the banker or custodian.

The tumbler 9 is pivoted to the post 10 in the usual manner and has attached thereto, 100 the usual spring 11. The tumbler 9 is provided with the downward projecting extension or flange 12, said flange being located in close proximity to the spindle 3 when said tumbler is in its lowermost position or 105 in the position illustrated in Fig. 9. When the key 13 is inserted in the key way 5 and turned into the position illustrated in Fig. 10, said key will bear against the edge of the flange 12 and move the free end of the tum- 110

bler up or into the position shown in Fig. 10, thereby bringing the slot 14 formed in the tumbler 9 into position to register with the tongue 15 carried by the lock bolt 16 at 5 which time the lock bolt is free to be brought into position to unlock the door so far as said particular tumbler is concerned. After the tumbler 9 has thus been lifted by the key carried by the banker or custodian, the key 10 carried by the depositor can be placed in the key way or slot 6 of the spindle 4 and the remaining tumblers common to locks of this nature actuated by said key whereby all of the tumblers are brought into position so 15 that all of the slots similar to the slot 14 will register with the tongue 15, after which the bolt can be moved endwise the tongue 15 entering the series of slots.

It will be understood that the ordinary 20 tumblers do not have to do with the present invention as they are not novel within themselves and hence no detailed illustration is deemed necessary as such parts are common and well known to those skilled in 25 the art.

The spindle 4 which is the one to be actuated by the depositor's key and the one provided with the slot or key way 6 is also provided with a transverse slot 17, into 30 which transverse slot the projection 18 is entered when the tumbler 9 is in its lowered position, or in the position illustrated in Fig. 9, and when the projection 18 is located in the slot 17, the depositor's key 19 35 cannot be put in the key way 6, but can be after the tumbler 9 has been elevated, as illustrated in Fig. 10. In deposit boxes such as are used by different depositors and where a large number or a given number of 40 different deposit boxes are assembled and the various boxes rented to different individuals it is of importance that the key ways of the spindles be protected in such a manner that the banker or custodian's key 45 cannot be inserted or placed in the spindle in the absence of the depositor, and in order to prevent the banker or custodian from tampering or in any way meddling with the lock I provide the key hole guards 20 and 50 21, the guard 20 being the one designed to be controlled by the depositor and the guard 21, being the one controlled or the one manipulated by the banker or custodian but these guards can both be operated by a single 55 person or by the banker or custodian or depositor, but the depositor's guard can not be removed until it is released as hereinafter described.

The key hole guard 20 is provided with 60 the slot 22 and when the guard is placed in proper position and in the position illustrated in Fig. 4 and the tumbler 9 located in the position illustrated in Fig. 9 said guard cannot be removed until it is re-

leased by the banker or custodian's key. 65 When the guard 20 is placed in position the cross notch or slot 22 is so located that it will register with the transverse slot 17 so that when the tumbler 9 is lowered the projection 18 will engage the slot or cross notch 70 22, thereby locking the guard in the key hole and in such a manner that it cannot be removed until the tumbler 9 is elevated and the extension 18 moved from the notch or slot 22. 75

The custodian's guard 21 is originally placed in the position shown in full lines Fig. 4, said guard being placed in the key way 5 and the notch 23, which notch is formed in the annular flange 24 located upon the sleeve 80 7 but after the guard has been brought into the position illustrated in full lines Fig. 1 and in dotted lines Fig. 4 the shoulder 25 will come in contact with the inner edge of the annular flange 24 so that the guard 21 85 cannot be removed until it is brought into the position illustrated in full lines Fig. 4 or until the key way registers with the notch 23, which notch provides clearance for the shouldered end of the key hole guard 21. 90

The key hole guards 20 and 21 are each provided with the flanges 26 and 27, which flanges are provided with the apertures 28 and 29 and when the key hole guards 20 and 21 are brought into the position illustrated 95 in Fig. 1 the apertures 28 and 29 will register, thereby providing a means for securing the key hole guards together, with reference to each other. It will be understood that there may be many ways and many devices employed for securing the key guards together, but I have illustrated one way which consists of what might be termed a seal hasp, which seal hasp as illustrated is made up of two members 30 and 31 hinged 100 together. The member 30 is provided with a disk or an enlarged end 32, which may be provided with a series of lugs 33. The member 31 is provided with the enlarged end or head 34, which is formed of a size so that 110 it can be placed upon the disk 32 and surrounded by the lugs 33. In case it is desired to seal the hasp ordinary sealing wax may be placed upon the hasp members and a seal of any desired form impressed upon the 115 sealing wax, by which arrangement the seal thus impressed will be a safe guard as against any tampering by a person or persons without authority. For the purpose of greater security the seal impressed upon the 120 sealing wax may be impressed by the gem of a ring worn by the depositor, thereby assisting in a further degree at least in identifying the depositor.

It will be understood that there may be 125 many other ways than the one just above described employed in sealing and for the purpose of illustration I have shown the ends

of the hasp members provided with apertures 35 and 36, through which apertures a wire may be placed and a lead seal employed or used.

5 Having fully described my invention what I claim as new and desire to secure by Letters Patent, is—

1. In a device of the character described, the combination of a lock casing, a series 10 of spindles carried by the casing, said spindles provided with key ways, one of the key ways provided with a transverse slot intersecting said key way, a tumbler provided with a projection adapted for contact with 15 one of the keys, said tumbler provided with a projection adapted for engagement with the transverse slot in one of the key ways, key hole guards adapted to be inserted in the key ways of the spindles, one of said key 20 hole guards provided with a slot adapted to register with the transverse slot of one of the key ways of the spindles, the projection of the tumbler adapted for engagement with the slot of the key hole guard and means for 25 securing the key hole guards in relative position independent of the means for locking one of the key hole guards to the spindle.

2. For a multiple key lock provided with 30 a plurality of adjacent key holes, a key hole guard comprising a plurality of guard members adapted to be entered into said key holes, means operated by the key in one key hole for maintaining the guard member in the adjacent key hole and the guard member 35 in said adjacent key hole adapted for movement while in said adjacent key hole toward and from the first guard member, and means for preventing the removal of

said second guard member when moved toward the first member.

3. For a multiple key lock having adjacent 40 separate depositor's and custodian's key holes, a depositor's key hole guard adapted for insertion into the depositor's key hole, means releasable by the custodian's key for 45 maintaining said depositor's guard in the depositor's key hole, and a custodian's key hole guard adapted for insertion into the custodian's key hole, and, when so inserted, adapted for movement toward and from 50 said depositor's key hole guard, and means for locking said guards together.

4. For a multiple key lock having separate 55 adjacent depositor's and custodian's key holes, a depositor's key hole guard adapted for insertion into the depositor's key hole, a tumbler within said lock adapted to be operated by the custodian's key and adapted to retain said depositor's key hole guard in 60 said depositor's key hole and custodian's key hole guard adapted to be inserted into the custodian's key hole, and, when so inserted adapted to be rotated toward and from 65 said depositor's key hole guard, means for locking said guards together, and means for preventing removal of the custodian's key hole guard when rotated toward said depositor's key hole guard.

In testimony that I claim the above, I have hereunto subscribed my name in the 70 presence of two witnesses.

BARTHOLOMEW F. KLOHS.
